UNITED STATES PATENT OFFICE.

THEODORE A. PERDIUE, OF TOLEDO, OHIO.

LOCK FOR MOTOR-VEHICLES.

1,314,426.

Specification of Letters Patent. Patented Aug. 26, 1919.

Application filed June 26, 1919. Serial No. 306,863.

To all whom it may concern:

Be it known that I, THEODORE A. PERDIUE, a citizen of the United States, and a resident of Toledo, in the county of Lucas and State of Ohio, have invented certain new and useful Improvements in Locks for Motor-Vehicles, of which the following is a specification.

My invention is an improvement in locks for motor vehicles, and has for its object to provide a lock of the character specified, of the permutation type, for locking the transmission controlling lever of a motor vehicle in neutral position.

In the drawings:

Figure 1 is a perspective view of the improved lock in place,

Fig. 2 is a top plan view of the lock detached,

Fig. 3 is a horizontal section,

Fig. 4 is a section on the line 4—4 of Fig. 2 showing the lock locked,

Fig. 5 is a similar view showing it unlocked,

Fig. 6 is a perspective view of the locking bolt,

Fig. 7 is a similar view of one of the locking pins.

The present embodiment of the invention is shown in connection with the **H** plate 1 of a motor vehicle, being designed to lock the transmission controlling lever 2 in neutral position, and to prevent if desired the full movement of the reverse lever 3. The improvement comprises a plate 4 having its under surface cut to fit to the upper face of the **H** plate, and this plate has depending lugs 5 which fit in slots of the **H** plate, to prevent lateral movement of the plate 4 with respect to the **H** plate.

The plate 4 has a notch 6 extending laterally inward from one side thereof, for receiving the transmission controlling lever 2, and in line with the center of the lever when fully in the notch plate has a longitudinally extending bore 7, the lever having a transverse opening 8 registering with the bore, when the lever is in place in the notch.

This bore is adapted to receive a locking bolt 9 having a knurled head 10 for convenience in manipulating the bolt, and this bolt has oppositely arranged series of transverse grooves 11, which are adapted to register with vertical openings 12 in the plate, the said openings extending from the upper face of the plate to below the level of the locking bolt. These openings are adapted

to receive locking pins 13, each of which has a head as shown abutting the upper face of the plate 4, and the pins of each series are held in place by a dowel pin 14 arranged in an opening in the plate 4, the locking pins having annular grooves 15 for receiving the dowel pins.

Each locking pin is provided with a rounded recess 16 intermediate its ends, which are at the level of the bore for the locking bolt, and these recesses are adapted to be turned into register with the bore for the locking bolt to permit the free passage of the locking bolt in movement of withdrawal or insertion.

It will be obvious that when all of the locking pins are turned to cause the recesses 16 to register with the bore 7, the locking bolt may be withdrawn or inserted, moving freely into or out of the bore. When however these pins are turned to bring the recesses 16 out of register with the bore 7, the locking bolt if out cannot be inserted, and if in cannot be withdrawn. Each locking bolt has in the top of its head a transverse groove or kerf 17, the heads being circular, and the kerfs being chords of the circle. These kerfs do not all bear the same relation to the recesses 16.

Referring to Fig. 2 it will be seen that eight locking pins are provided, four on each side of the locking bolt, and the kerfs are so arranged that when the bolt is unlocked, the kerfs will show a certain definite pattern, certain of the kerfs being perpendicular with the bolt, others parallel therewith and others may be at angles of 45°. In Fig. 2 the pins are shown arranged and unlocked, while in Fig. 3 they are shown locked. The pins may be arranged to be turned by the finger or thumb or with a tool, as for instance a screw driver.

The plate 4 cannot be engaged with the slots of the **H** plate until the lever 2 is in neutral position, and it will be seen referring to Figs. 1 and 3 inclusive that a notch 18 is provided for receiving the reverse lever 3. This notch prevents complete movement of the reverse lever from one end of the **H** plate to the other.

I claim:

1. In a motor vehicle, the combination with the **H** plate and the transmission controlling lever, of means for locking said lever in neutral position, said means comprising a plate having lugs depending into

the slots of the **H** plate and having a notch registering with the neutral passage of the **H** plate when the lugs are engaged with the slots and adapted to receive the lever, said plate having a bore for a locking bolt extending transversely of the notch, and the lever having an opening registering with the bore when the lever is in the notch, a locking bolt movable in the bore, and a series of locking pins for locking the bolt in place, said pins being journaled in the plate and extending into the bore and having recesses registering with the bore when the pins are in certain positions, the locking bolt having recesses registering with the pins.

2. In a motor vehicle, the combination

with the **H** plate and the transmission controlling lever, of means for locking said lever in neutral position, said means comprising a plate having lugs depending into the slots of the **H** plate and having a notch registering with the neutral passage of the **H** plate when the lugs are engaged with the slots and adapted to receive the lever, said plate having a bore for a locking bolt extending transversely of the notch, and the lever having an opening registering with the bore when the lever is in the notch, a locking bolt movable in the bore, and a series of locking pins for locking the bolt in place.

THEODORE A. PERDIUE.
